UNITED STATES PATENT OFFICE

2,041,801

BEACON

Channing Whitman, Buffalo, N. Y., assignor to
Flexlume Corporation, Tonawanda, N. Y., a
corporation of New York

Application September 14, 1929, Serial No. 392,668

2 Claims. (Cl. 177—329)

This invention relates to improvements in beacons of the kind in which neon or other suitable electroluminescent tubes are employed and proposes a construction which, altho available for other purposes, is especially desirable as a warning marker to indicate to aviators the presence of dangerous obstacles, such as towers carrying high voltage lines.

The use of neon tubes for this purpose is particularly desirable because of the fog penetrating power of the light produced by such tubes. Altho such a tube possesses this desirable characteristic, the length of its life is uncertain, and for this reason its arrangement and connection in the ordinary manner would be objectionable for the particular purpose in view since its failure would permit the obstacle to remain unmarked until such failure was noted and remedied. Even a failure for a short period, a matter of hours, might result in an accident, particularly if the obstacle were near an airport or along a frequently used route of flight.

One object of the invention is to overcome the above objections to the use of electroluminescent tubes in the marking of obstacles. A further object is to provide a marker of the type described which will produce a continuous light of substantially uniform intensity over a relatively long period of time, the marker not being rendered inactive by the failure of an illuminated tube.

A further object is to provide a marker in which in the event of failure of a tube another will automatically come into operation with characteristics which will indicate to one familiar with the installation that it has succeeded in operation the tube with which the operation started. This fact can be noted by a simple inspection of the marker when illuminated and thus the defective tube can be replaced, the marker continuing in operation until the replacement is made, assuming, as will be the fact in connection with a regular and orderly inspection, that the replacement is made within a reasonable time.

The invention contemplates the arrangement in any desired manner of a plurality of electroluminescent tubes of varying resistances and connected in parallel. Preferably the variations of resistance are obtained by using tubes of different lengths. In such an arrangement the current, taking the path of least resistance, effects the illumination of the shortest tube in the group the other tube or tubes remaining inactive until the failure of the illuminated tube at which time the path of current is immediately

shifted to include the next longer tube, the particular tube illuminated at any one time serving to indicate the condition of the remaining tube or tubes in the group.

An embodiment of the invention is illustrated in the accompanying drawing in which:

Figure 1 is a plan view of an obstacle marker in which the features of the invention are incorporated.

Figure 2 is an end view of the same.

Figure 3 is a longitudinal section through the body of the marker.

Figure 4 is a fragmentary section of the preferred type of electroluminescent tube with which the marker is equipped.

The obstacle marker may be of any appropriate shape or form. As shown it is in the form of a T. It may be provided with any suitable number of pairs or groups of tubes operating successively in the manner generally described.

The marker consists of a casing C in which all operating parts except the tubes are mounted and which is of T shape, being preferably so arranged that its central leg and its end bar are in a horizontal plane. In the construction illustrated the marker is provided with two pairs of tubes, the tubes of one pair A being arranged above the central leg of the casing and the tubes of the other pair B being arranged in front of the end leg of the casing, the tubes of pair A extending horizontally and being in a common horizontal plane and the tubes of pair B extending horizontally and being in a common vertical plane. The tubes of pair A are designated 5 and 6 respectively and the tubes of pair B are designated 7 and 8 respectively. In pair A the tube 5 is the shorter tube and the tube 6 is the longer tube and in pair B the tube 7 is the shorter tube and the tube 8 is the longer tube. Each pair of tubes preferably has its own multiple circuit and at the start of the operation of the beacon the shorter tubes of each pair are simultaneously illuminated. While the differences between the lengths of the tubes of a pair together with the differences in their locations, the tube 6 at the right and the tube 5 at the left and the tube 7 above and the tube 8 below (the drawing being considered), are sufficient to enable an observer or inspector familiar with the installation to determine which tube of each pair is operating, the differentiation between the tubes of a pair may be made more marked, if desired.

Altho any desired type of tube may be employed I preferably employ a tube of the construc-

tion shown in Figure 4, which construction is the subject of the Patent No. 1,746,024 of Feb. 4, 1930, of Alfred L. Brandt. This construction consists generally of a spirally formed luminescent tube 5 11 enclosed within a substantially rigid glass cylinder 12, which cylinder acts as a support for the somewhat flexible luminescent tube which gives a display having the appearance of a continuous band of light equal in width to the diameter of the cylinder 12. The casing C is provided with suitable receptacles 9 for cooperation with the terminal portions of the tube, the casing having openings registering with said receptacles through which the terminal portions are inserted. 10

15 Suitable transformers 12 and 13 are mounted within the casing C, the primary or low voltage sides of the transformers being connected in parallel to a suitable source of energy (not shown) by the line wires 14 and 15. The tubes 5 and 6 of pair A are connected in parallel as by wires 16 and 17 to the secondary or high voltage side of the transformer 12 while the tubes 7 and 8 of pair B are similarly connected as by wires 18 and 19 to the high voltage side of the transformer 13. 20

25 From the arrangement illustrated it will be noted that upon the connection of the line wires 14 and 15 to a suitable source of supply, the current will pass through wire 16, the shorter tube 5, and wire 17 back to the transformer 12, no current at all passing through the longer tube 6 which offers greater resistance to passage of the current than the tube 5. In like manner and at the same time the current will pass through wire 18, the shorter tube 7 and wire 19 back to the 30 transformer 13, no current at all passing through the longer tube 8 on account of the greater resistance which it offers. However, each of the shorter tubes 5 and 7, upon failure, will offer a greater resistance to the flow of current than the corresponding larger tubes 6 and 8 and the resistance in a shorter tube increasing sufficiently the current will change its path to include the corresponding longer tube. 35

40 It is to be noted that the voltage required to start an electroluminescent tube is much greater than that required to maintain it in an illuminated condition. For instance, where a tube is of such length as to require approximately 14,000 volts to start the flow of current, 10,000 volts would ordinarily be sufficient to maintain the operation. With this in mind, it will be understood that if for example, two tubes are connected in parallel, the longer tube requiring 14,000 volts 45 to start it and the shorter tube requiring only 12,000 volts, then the shorter tube will be illuminated when the voltage of the current from the source of supply has been raised to 12,000 volts. Thereupon, as the resistance of the tube falls to a normal operating value, the transformer will immediately reduce the voltage to in the neighborhood of 9,000 volts, this E. M. F. being sufficient to maintain the operation. During the 50 continued use of this shorter tube, and as the gaseous conducting medium therein is gradually dissipated, its resistance builds up to and approaches the resistance of the longer tube, that is to say, the tube requiring an E. M. F. of 14,000 volts to start it. When the resistance of the shorter tube has become greater than the starting resistance of the longer tube, the latter will be started but after being started, its operating resistance being less, an E. M. F. of approximately 55 10,000 volts will be adequate to maintain the op-

eration and the transformer will immediately reduce the voltage to this amount.

From the example given it will be obvious that the two tubes will produce a light of substantially uniform intensity over a period of time 5 equal to the sum of their lives and that the tubes will not become ineffective for any appreciable length of time during the period that the current shifts from the shorter tube to the longer tube, this being due, as mentioned here- 10 fore, to the fact that as soon as the E. M. F. required to illuminate the shorter tube has become sufficient to start the longer tube and does start such tube, the E. M. F. required to illuminate the longer tube is immediately reduced to 15 such an extent as to be entirely inadequate to affect the shorter tube. For this reason it is im- 20 possible at the time that the resistance of the shorter tubes has been built up to the starting resistance of the longer tubes to have a condition where the path of the current will shift back and forth between the two tubes. In this connection it is to be understood that when the dis- 25 sipation of the gaseous conducting medium in a tube reaches an advanced stage the operating voltage of the tube is not only increased but the brilliancy of the tube is materially impaired. The relative starting voltages of the tubes are, therefore, predetermined so that the illumination of a substitute tube will be effected before 30 the gaseous conducting medium in the tube which it is to succeed has become dissipated to such an extent that the brilliancy of the latter is reduced to a point where it is unsuitable for the purpose in view. Likewise it is to be un- 35 derstood that if the tube which is initially il- 40 luminated should fail for any other reason, as for example by being broken, the illumination of the substitute tube will be automatic and instantane- 45 ous.

An advantage obtained by this arrangement of tubes is that the particular tube illuminated serves to indicate the condition of the other tubes in its group, that is to say, in the form illustrated, when the longer tube 6 is illuminated it 45 is a warning that the shorter tube 5 has failed and should be replaced, the longer tube substituting in the meantime for the inactive shorter tube until such replacement.

It will, of course, be obvious that the particular arrangement or number of tubes may be varied depending, in each instance, upon the purposes in view, the arrangement shown being merely for the purpose of illustration.

Having fully described my invention, I claim:

1. A beacon or similar device including a support and a plurality of exposed gaseous discharge tubes which are connected in parallel and which are located in relatively close proximity with respect to one another, each of the said tubes being adapted to provide a light of substantially the same intensity, the said tubes being illuminated one at a time as the breaking down of one tube automatically effects the illumination of a companion tube of greater resistance, whereby to provide a continuous light of substantially uniform intensity, the resistances of said tubes increasing progressively in such degree that their order of illumination is certain and predetermined, the arrangement of 60 said tubes upon said support being predetermined and in accordance with their order of illumination, whereby the tube which is illuminated at any particular time serves to indicate whether there has been a failure of any of the 70 75 80 85 90 95 100

remaining tubes and if there has been such a failure what particular tubes are involved.

2. A beacon or similar device including a support and a plurality of differently shaped ex-
5 posed gaseous discharge tubes which are con-
nected in parallel and which are located in rela-
tively close proximity with respect to one an-
other, each of the said tubes being adapted to
provide a light of substantially the same intensi-
ty, the said tubes being illuminated one at a time
as the breaking down of one tube automatically
10 effects the illumination of a companion tube of
greater resistance, whereby to provide a contin-

uous light of substantially uniform intensity,
the resistances of said tubes increasing progres-
sively in such degree that their order of illumi-
nation is certain and predetermined, said tubes
progressively increasing in length and their ar-
rangement upon said support being in accord-
ance with their order of illumination, whereby
the tube which is illuminated at any particular
time serves to indicate whether there has been
a failure of any of the remaining tubes and if
there has been such a failure what particular
tubes are involved.

CHANNING WHITMAN.
